UNITED STATES PATENT OFFICE.

GEORGE W. LEWIS, OF GRINNELL, IOWA, ASSIGNOR TO GRINNELL WASHING MACHINE COMPANY, OF GRINNELL, IOWA.

GEARING DEVICE FOR WASHING-MACHINES.

1,231,918.

Specification of Letters Patent. Patented July 3, 1917.

Application filed February 7, 1917. Serial No. 147,241.

To all whom it may concern:

Be it known that I, GEORGE W. LEWIS, a citizen of the United States, and resident of Grinnell, in the county of Poweshiek and State of Iowa, have invented a certain new and useful Gearing Device for Washing Machines, of which the following is a specification.

The object of my invention is to provide a gearing device of simple, durable and inexpensive construction, especially designed for use in connection with washing machines, said gearing device being adapted to move an agitating member that is pivoted above the center of the tub in a direction for swinging it in a vertical plane back and forth across the center of the tub, and at the same time progressively moving its pivotal point in a direction circumferentially around the tub, so that each swinging movement of the agitator passes through the body of the tub at an angle different from the preceding movement, to thereby produce a maximum of agitation of the soapy water and a maximum of movement of the clothes to present new surfaces to the action of the agitator and moving water, with a minimum of applied power.

My invention consists in the construction, arrangement and combination of the various parts of the device whereby the objects contemplated are attained, as hereinafter more fully set forth, pointed out in my claims, and illustrated in the accompanying drawings, in which:

Figure 1 shows a vertical, central, sectional view through a gearing device embodying my invention, and applied to a washing machine.

Fig. 2 shows a top or plan view of the same, and

Fig. 3 shows an enlarged, detail, sectional view on the line 3—3 of Fig. 1.

Referring to the accompanying drawings I have used the reference numeral 10 to indicate the body of a washing machine, and 11 the hinged cover. Mounted in the central portion of the hinged cover is a rotatable plate 12 having a ratchet toothed rim 13 extending around its upper surface, and being supported for rotation within the cover by the supporting plate 14.

Near the central portion of the plate 12 are the upwardly projecting brackets 15 in which is supported a shaft 16. Mounted on

this shaft is a hub 17 having two arms 18 projected at right angles to the hub, each provided with an antifriction roller 19. Extending downwardly from the hub is the agitator arm 20 secured to the lower end of 60 which is an agitator 21, preferably closed at its top portion and open at its bottom portion, as shown.

By the arrangement shown the agitator may be made to swing back and forth 65 through the tub from its pivotal point above the hinged cover. The dotted lines in Fig. 2 show the position of this agitator when at its limit of movement opposite from the position shown by solid lines.

So long as the supporting plate 12 remains stationary this agitator will swing back and forth through the tub in the same path. However, if the supporting plate 12 is moved by being rotated part of a revolution, it is obvious that further swinging movement of the agitator will cause it to move through the tub along an entirely different path of travel.

I have provided for imparting to the agitator the swinging movement across the tub and also for imparting to the plate that supports the agitator a step by step rotary movement to change the path of travel of the agitator through the tub, as follows:

Mounted on top of the hinged cover is a supporting bracket 22 having mounted in its central portion an upright shaft 23. This shaft has an arm 24 at its upper end, connected to a rod 25, which rod extends outwardly toward the side of the washing machine and is attached to an operating lever 26.

On the lower end of the shaft 23 is a balance wheel 27, having at its central portion 95 a circular downwardly projecting cam 28, which cam is designed to engage the rollers 19. By this arrangement it is obvious that when the lever 26 is reciprocated the balance wheel 27 will be rotated and the cam 28 will 100 act upon the arms 18 through the rollers 19 in such manner as to swing the agitator back and forth through the body of the tub.

For rotating the supporting plate 12 step by step as the agitator is swung, I have provided a rod 29 pivoted to the lever 26 and extended through a guide 30 and having its free end designed to engage the ratchet teeth 13, so that during each movement of the lever 26 the rod 29 will act as a pawl and en-

gage one of the teeth 13 and rotate the supporting plate 12 one tooth space, so that each time that the agitator is rocked or reciprocated across the center of the tub its path of travel will be slightly changed, thus causing the agitator to move the clothes about within the tube to present new surfaces to the action of the agitator and the water currents.

- 10 In practical use the soapy water and clothes are placed within the tub in the ordinary way, and after the cover is closed the lever 26 is reciprocated by the operator or in any suitable manner. This movement of 15 the operating lever causes the balance wheel 27 to be rotated, and the rotation of the balance wheel effects the rocking or reciprocation of the agitator as described. At the same time the supporting plate 12 which 20 carries the agitator is rotated step by step through the action of the rod or pawl 29 and the ratchet rim 13, so that during a washing the agitator progressively swings across the center of the tub at various angles, and when 25 a complete revolution of the plate 12 has been made the agitator will have operated directly upon all of the clothes contained within the tub, and at the same time will have caused the clothes to move around 30 within the tub and to present new surfaces to the action of the agitator and the water.

As the agitator 21 is moved upwardly, there will be a suction through the clothes, and as it moves downwardly there will be a 35 tendency to force air downwardly through the water and the clothes.

This pumping or alternate suction and forcing action is quite noticeable when the machine is being operated, and serves to 40 more thoroughly agitate the clothes and water and more thoroughly draw and force the water through the clothes.

As the agitator 21 moves upwardly, the air suction will tend to hold the part of the 45 clothes against the agitator and raise them, and as the agitator moves around, part of the clothes are carried with it so that the clothes are worked up and down and around

constantly when the machine is in operation. It will thus be seen that the clothes are constantly moved and agitated without being subject to the friction and wear which would be imposed by the ordinary dolly.

It may be obvious that my improved gearing device is of extremely simple and inexpensive construction, and all of the parts are strong and durable and not likely to get out of order.

I claim as my invention:

1. In a gearing device of the class described, the combination of a rotatable plate, an arm pivotally supported in the plate and extended downwardly, means for imparting a step by step rotary movement to the plate, and means for imparting a swinging movement to said arm when the plate is in any position of its movement.

2. In a gearing device, the combination of a rotatable plate, an arm pivotally supported in the plate and extended downwardly, ratchet teeth on the plate, a rotatable wheel above said plate, a cam carried by the rotatable wheel and capable of engaging and rocking the said arm, a lever, means connected with said lever for imparting a rotary movement to the said wheel, and a pawl connected with said lever to engage said ratchet teeth, for the purposes stated.

3. In a device of the class described, the combination of a plate mounted for rotation, a ratchet rim formed thereon, an arm pivotally supported by the plate and extended downwardly through the plate, two rollers connected with said arm and extended in opposite directions from the pivotal center of the arm, a balance wheel supported above said arm, a cylindrical downwardly extended cam connected with the balance wheel and designed to engage said rollers, a pitman connected with the lever and designed to coöperate with the said ratchet pitman, and means connected with the lever for rotating the said balance wheel, for the purposes stated.

Des Moines, Iowa, April 8, 1916.

GEORGE W. LEWIS.
